ABSTRACT: A frame time base system for television receivers and the like. The system is built around a cold-cathode glow discharge tube having an anode, a grid, a trigger electrode and a cathode, a first source of positive potential connected to the anode through a first resistor, a capacitive network connected to the anode and the first resistor to form a sawtooth wave generator for the output of the discharge tube, a resistor network connected between the trigger electrode and the grid, a source of synchronizing pulses supplied through the first portion of the resistor network to the triggering electrode and through a second portion of the resistor network to the grid, and a second source of positive potential connected through a second resistor to the resistor network.

FRAME TIME BASE FOR TELEVISION RECEIVERS

The present invention relates to television, and more particularly to frame time base systems for television receivers. The prior art includes frame time bases for television receivers, using cold-cathode glow discharge tubes. In such time bases, the tube has a cathode, a trigger electrode, a grid, and an anode sequentially arranged. The trigger electrode serves to reduce the erratic delay in starting the main-gap discharge and is connected to a source through a current-limiting resistor. The grid is held positive with respect to the cathode and is fed frame-synchronizing pulses.

A disadvantage of prior art frame time base systems is that variations in the starter-gap discharge current, bias voltage or supply voltage impairs the synchronization such that additional controls are provided for adjustment.

Another disadvantage is that such time base systems require high-quality resistors, capacitors and tubes manufactured to extremely close tolerances.

An object of the present invention is to provide a frame time base system which dispenses with the need for additional adjustment controls and is capable of stable synchronization even under the influence of marked variations in the voltages applied and the ratings of the circuit components.

This and other objects are accomplished in accordance with the principles of the present invention by providing a frame time base system using a cold-cathode glow discharge tube whose anode circuit contains an RC-network to produce a sawtooth voltage, in which, according to the invention, there are resistors placed between the trigger electrode and the grid in order to decrease the grid potential with respect to the trigger electrode in the course of time base operation, while the circuit through which the grid is fed synchronizing (sync.) pulses contains some of these resistors whose resistance is made sufficiently high to prevent relaxation oscillations occurring in the electrode circuits.

Connection of the tube electrodes and the injection of sync. pulses, according to the invention, the anode breakdown voltage is held fixed and the stability of synchronization is maintained due to the fact that variations in the starter-gap discharge current compensate for variations in the grid potential.

The invention will be more fully understood from the following description of a preferred embodiment, when read in connection with the accompanying drawing which is a schematic diagram of a frame time base system for television receivers, according to the invention.

A frame time base system, according to the invention, comprises a cold-cathode glow discharge tube 1 in which a trigger electrode 2 and a grid 3 are sequentially arranged between a cold cathode 4 and an anode 5. Connected to the anode 5 is an RC-network network made of a resistor 6 connected to a source E_1 , and series capacitors 7 and 8. The capacitor 8 blocks the DC component due to E_1 from the sawtooth voltage derived across the capacitor 7. The trigger electrode is connected through a resistor 9 to another source E_2 . In some cases, the resistors 6 and 9 may be connected to the positive side of a common source. The grid 3 is connected through series resistors 10 and 11 to the trigger electrode 2. The vertical scan sync. pulse source (omitted in the schematic) is connected to the common junction of the resistors 10 and 11 through a DC blocking capacitor 12.

The connection of the vertical scan sync. pulse source through the capacitor 12 as shown in the schematic may cause relaxation oscillations in the trigger electrode and grid circuits; to prevent them, the resistors 10 and 11 have sufficiently high values of resistance.

The output sawtooth voltage of the frame time base herein disclosed is derived in the conventional manner. The capacitors 7 and 8 are charged by the source E_1 through the resistor 6. When the anode voltage reaches the breakdown value or when a sync. pulse is applied to the grid 3 through the resistor

10, the capacitors 7 and 8 discharge through the tube 1. The relatively low rate of charge of the capacitor 7 and its rapid discharge result in sharp sawtooth voltage pulses at the output.

The detailed description that follows describes the portion of the time base responsible for the stable synchronization of the frame frequency.

When the supply voltage is turned on, a triggering discharge occurs across the starter-gap between the trigger electrode 2 and the cathode 4, characterized by a constant voltage drop over a broad range of current. Since the grid 3 is placed near the trigger electrode 2, a transfer current begins to flow between the grid and the starter-gap discharge, giving rise to a voltage drop across the resistors 10 and 11 and reducing the potential at the grid 3 relative to the trigger electrode 2. The transfer current and, consequently, the fall of the grid potential increase with increase of the starter-gap current. In cold-cathode glow discharge tubes, the anode breakdown voltage decreases with increase of starter-gap current and of grid potential.

Thus, connection of the electrodes 3 and 2 through the resistors 10 and 11 provides for the stabilization of the anode breakdown voltage. If, for example, the starter-gap current should increase due to an increase in the supply voltage or the aging of the resistor 9 or the tube 1, the transfer current will also increase, further decreasing the potential at the grid 3, thereby stabilizing the anode breakdown voltage. A decrease in the starter-gap current reduces the potential at the grid 3, and the anode breakdown voltage is again stabilized.

From the foregoing it follows that the anode breakdown voltage remains practically constant against variations in supply voltage, tube characteristics, or resistor ratings. As a result, the synchronization of the frame frequency is stabilized to a high degree.

The invention herein disclosed provides for stable synchronization with small-amplitude sync. pulses against marked variations in supply voltage and two-fold changes in resistor ratings, and also makes redundant any synchronization adjustment controls.

What is claimed is:

40. 1. A frame time base system for television receivers and the like comprising a cold-cathode glow discharge tube having an anode, a grid, a trigger electrode and a cathode, a first source of positive potential connected to said anode through a first resistor, a capacitive network connected to said anode and said first resistor to form a sawtooth wave generator for the output of said discharge tube, a resistor network connected between said trigger electrode and said grid, a source of synchronizing pulses supplied through a first portion of said resistor network to said triggering electrode and through a second portion of said resistor network to said grid, and a second source of positive potential connected through a second resistor to said resistor network.

45. 2. A system as claimed in claim 1, wherein said capacitive network include, first and second capacitors connected in series between said anode and a point of ground potential, said sawtooth waveform being developed across said second capacitor.

50. 3. A system as claimed in claim 1, wherein said resistor network is formed by third and fourth resistors connected in series, said triggering electrode connected to one end of said third resistor, said grid connected to one end of said fourth resistor, said source of synchronizing pulses applied to the other ends of said third and fourth resistors, said other ends being connected together.

55. 4. A system as claimed in claim 3, including a third capacitor wherein said source of synchronizing pulses are supplied to said other ends of said third and fourth resistors through said third capacitor, said third and fourth resistors being of a sufficiently high value to prevent relaxation oscillations.

60. 5. A system as claimed in claim 1, wherein said first and second sources of positive potential are the same.
